UNITED STATES PATENT OFFICE.

SAMUEL ALPERN, OF PITTSBURGH, PENNSYLVANIA.

DESIGN FOR A STOCKING.

Application filed March 15, 1929. Serial No. 30,491. Term of patent 7 years.

To all whom it may concern:

Be it known that I, SAMUEL ALPERN, a citizen of the United States, residing at Pittsburgh, in the county of Allegheny and State of Pennsylvania, have invented a new, original, and ornamental Design for a Stocking, of which the following is a specification, reference being had to the accompanying drawing, forming part hereof.

The figure of the drawing is a rear view of a stocking showing my design, the characteristic feature of which resides in the figure of a butterfly and flower.

What I claim is:

The ornamental design for a stocking, substantially as shown and described.

In testimony whereof, I hereunto set my hand.

SAMUEL ALPERN.
